ATTORNEYS.

UNITED STATES PATENT OFFICE.

GEORGE D. ILLIG, OF DEPEW, NEW YORK, ASSIGNOR TO BARCALO MANUFACTURING COMPANY, OF BUFFALO, NEW YORK.

WRENCH.

1,426,647.

Specification of Letters Patent. Patented Aug. 22, 1922.

Application filed August 6, 1921. Serial No. 490,320.

To all whom it may concern:

Be it known that I, GEORGE D. ILLIG, a citizen of the United States, residing at Depew, in the county of Erie and State of New York, have invented a new and useful Improvement in Wrenches, of which the following is a specification.

This invention relates to improvements in wrenches, and more particularly to wrenches of the kind having a movable jaw which is slidable lengthwise of a shank or handle toward and from a fixed jaw.

The objects of this invention are to provide a wrench of this kind comprising a body portion made of a single piece of sheet metal bent to form a fixed jaw which is integral with a hollow shank or handle in which a shank of the movable jaw is slidably arranged, the hollow shank or handle being formed in such a manner as to present a finished appearance and to produce a joint between the meeting edges of the piece of sheet metal which will not cut into or otherwise injure the hand of a person using the wrench; also to provide a wrench of this kind which consists of only two sheet metal parts and an adjusting nut, and which is inexpensive to manufacture and reliable in operation; also to improve the construction of wrenches in other respects hereinafter specified.

In the accompanying drawings:

Fig. 1 is a side elevation of a wrench embodying the invention.

Fig. 2 is an edge view thereof.

Fig. 3 is a sectional elevation thereof showing the interior of the hollow shank or handle.

Fig. 4 is a view of a blank from which the body of the wrench is made.

Fig. 5 is a view of the blank partly formed.

Fig. 6 is a top edge view of the blank shown in Fig. 5.

Fig. 7 is a transverse sectional elevation of the wrench, on an enlarged scale on line 7-7, Fig. 3.

Fig. 8 is a fragmentary edge view of a wrench of slightly modified construction.

The wrench embodying the invention comprises a body portion A which is made of sheet metal and bent to form a hollow shank or handle portion 10 and having two projecting parts secured together to form a fixed jaw 11 which is integral with the handle portion, and a movable jaw member

B which has a shank or guide portion 12 entering into the hollow handle 10 and a jaw portion 13 which is movable toward and from the fixed jaw 11. The lower end of the shank of the movable jaw member is provided with a threaded stem or part 14 formed integral with the movable member of the wrench and adapted to be engaged by means of an adjusting nut C, which extends through holes 15 in the handle portion 10. The body portion of the wrench and the movable jaw member are both formed of sheet metal, the movable jaw portion being punched or cut in the desired shape and having the threads cut on the part 14 in the usual manner.

The body portion A of the wrench may be made from a flat blank such as shown in Fig. 4 having a body portion 17 which is adapted to be bent along the lines indicated by 18-18 so that the longitudinal middle portion of the blank forms the back edge of the body portion or handle of the wrench, and the parts of the blank adjacent to the middle portion form the opposite sides of the hollow handle. The blank is also provided with laterally extending portions 19 which are adapted to be bent or offset along the lines 20 as indicated in Figs. 5 and 6 so that when the body portion of the wrench is bent along the lines 18-18 the two jaw portions 19-19 will lie flat against each other and thus form a fixed jaw which is twice the thickness of the metal from which the body portion of the wrench is made. At the same time, the portions 19 form, along the lines 20 on which they are bent or offset, a fixed guide edge or portion of considerable length, which, together with the rear side of the body between the lines 18-18, cooperate to provide a snugly fitting guideway for the shank portion of the movable jaw to the extreme upper edge of the body portion, thus preventing any excessive "play" between the movable jaw and the body portion when the wrench is in use. When the blank from which the body portion is made is bent into the desired form, the two jaw portions 19-19 are preferably in intimate contact with one another and are secured together in any suitable manner, by rivets 25 or other suitable holding means, thus holding the parts of the body portion of the wrench in correct relation to each other.

The two holes 15 in the blank are also

brought opposite to each other by the bending of the blank so as to receive the adjusting nut C. The lower side portions of the blank are preferably bent along the lines 5 21—21, thus forming on the blank shown in Fig. 5, two forwardly extending marginal portions 22 which when the blank is bent along lines 18—18, extend toward each other as indicated in Fig. 2, and form the 10 front edge portion of the handle of the wrench. These two marginal portions 22 meet at about the middle of the edge portion of the wrench to form a butt joint which is neat in appearance and which 15 makes it possible to construct the body portion of the wrench with rounded corner portions or edges and thereby produce a handle on the wrench which does not cut into or otherwise injure the hand of the 20 person using the wrench.

The blank is preferably provided with recesses 23 which separate the lines 20 and 21 along which the blank is to be bent. These recesses greatly facilitate the bending 25 of the blank owing to the fact that the bend which the metal is given along the lines 20 is different from that which the metal is given along the lines 21.

The movable jaw member B is preferably 30 formed of sheet metal of approximately twice the thickness of that used in the body portion of the wrench, so that the jaw 13 will be approximately of the same thickness as the jaw 11 formed of the two continuing 35 portions 19 of the body portion. The shank portion 12 of the movable jaw member fits snugly into the hollow handle portion and acts as a guide for the movable jaw member. The stem 14 which is formed 40 integral with the shank portion 12 is preferably threaded by means of the ordinary thread cutting dies, which leaves the stem portion flat on opposite sides and threaded on the opposite edge portions.

45 In the manufacture of the body portion of the wrench, a blank such as shown in Fig. 4 is first stamped or cut out and is then bent along the lines 20 and 21, which gives the blank the appearance shown in 50 Figs. 5 and 6. The blank is then bent along the lines 18—18 which places the parts of the blank into their operative positions with regard to each other. The parts are then held or secured in this position by means 55 of the rivets 25 or other suitable means. The adjusting nut is then inserted into the openings or holes 15 of the handle and the shank of the movable jaw is inserted into the hollow handle so that the nut engages 60 the threaded stem 14 of the movable jaw.

If desired, the thickness of the fixed jaw of the wrench may be increased by placing an insert 26 between the two jaw parts of

the body portion of the wrench, as shown in 65 Fig. 8. When this construction is employed, the movable jaw member may be made of thicker metal, if desired.

The wrench described is simple and inexpensive to manufacture and is very reliable 70 in operation since the adjusting nut C engaging the threaded portion 14 of the shank of the movable jaw makes it possible to adjust the movable jaw relatively to the fixed jaw much more readily than in the 75 case of the adjusting worm usually employed. The bending of the edges 22 of the handle portion so that the joint between the edges of the blank is formed intermediate of one of the edges of the handle portion, makes it possible to round off all of the corners of the handle portion of the wrench, thus producing a smooth and well rounded handle and avoiding injury to the 80 hand of the person using the wrench. 85

I claim as my invention:

1. In a wrench, the combination of a body portion having a fixed inner jaw formed integral with a hollow handle, said body portion being made of a sheet metal blank, 90 the longitudinal middle portion of which forms the rear edge of said body portion and the portions of said blank adjacent to said middle portion forming the sides of the body portion, and the side edges of said blank having parts which are bent at substantially right angles to said side portions and are adapted to abut at approximately the middle of the front edge of said body portion, a movable outer jaw member 100 stamped from a sheet of metal of approximately twice the thickness of the blank from which said body portion is made, and having a shank portion arranged in said hollow handle to guide the movement of 105 said movable jaw, and a threaded stem, said shank portion, said stem and said movable outer jaw being of the same thickness, and a nut engaging said threaded stem for adjusting said movable jaw relatively to said 110 fixed jaw.

2. In a wrench, the combination of a one piece sheet metal blank comprising a hollow handle portion and duplicate fixed jaw forming portions bent to contact with one another, means for securing said fixed jaw forming portions together, whereby the fixed jaw is formed of two thicknesses of the metal of the blank, a movable jaw member stamped from a sheet of metal and having a jaw, a shank portion and a stem all of the same thickness throughout, and means in said handle portion engaging said stem for adjusting said movable jaw toward and from said fixed jaw. 115 120
